UNITED STATES PATENT OFFICE.

EMORY E. TROWBRIDGE, OF KANSAS CITY, KANSAS.

DRAIN-TILE.

1,393,329.

Specification of Letters Patent.

Patented Oct. 11, 1921.

Application filed April 5, 1920. Serial No. 371,272.

To all whom it may concern:

Be it known that I, EMORY E. TROWBRIDGE, a citizen of the United States, residing in the city of Kansas City, county of Wyandotte and State of Kansas, have invented certain new and useful Improvements in Drain-Tiles, of which the following is a specification.

My invention relates to improvements in drain tile and refers more particularly to a cup socket tile used in drainage systems to carry off superfluous moisture from improperly drained subsoil.

Among its salient objects are to provide a type of drain tile constructed to facilitate the removal of moisture from the subsoil; to provide a drain tile which when connected to form a drainage system produces a more mobile circulation of the water and air in the subsoil and permits the surface atmosphere to permeate more quickly to the body of the soil, causing the excess moisture to drain more readily therefrom; to provide a drain tile that is not easily waterlogged and tiles that are adapted to be connected up in any drainage system; to provide a tile that is cheap to manufacture and tile sections that are easily connected into a system, and in general to provide a tile of the character referred to.

In the drawings:

Figure 1 is a plan view of the top half of a drain tile used in the horizontal ducts.

Fig. 2 is a plan view of a section of the lower half of a drain duct as laid with the connecting tiles broken away.

Fig. 3 is a side elevation of view shown in Fig. 2.

Fig. 4 is a sectional end view of the drain as laid.

Fig. 5 is a perspective view of a connection of the vertical ducts with parts broken away and parts shown in section.

Fig. 6 is a side elevation of the upper half of the tile section, showing a portion of an adjoining tile section.

Fig. 7 is a view showing the interior of one of the top tile sections.

Fig. 8 is a side elevation of a lower tile section showing a portion of an adjoining tile.

Fig. 9 is a sectional view taken on the line 9—9 in Fig. 3.

In draining the moisture from the subsoil in farm lands or from road beds of railroads, public highways or pavements of any

sort, drain tile of a porous clay substance or a vitrified clay is commonly used. Where the porous tile is used, difficulties have often been encountered with the tiles becoming waterlogged and a consequent sluggish movement of the water from the subsoil through the drains. As a remedy for these difficulties, I have constructed a tile which is adapted to be used in any type of drainage system where the moisture is to be taken from the subsoil and atmospheric air supplied thereto. For the purpose of draining the water, I employ in the horizontal ducts of the system, a tile shown in Figs. 1, 2, 3 and 4 of the drawings.

This tile comprises two semi-cylindrical portions, 1 and 2, the lower portion having enlarged flanges 3 along its longitudinal edges, which have flaring lips 3a. The upper portions 2 are set into the socket formed by the shoulder of this enlarged flange forming an open channel 4 with the flaring lip 3a. At one end of both the upper and lower portions are enlarged flanges 5 which overlap the tubular body portions 6 of the adjoining tiles, thereby making a snug pipe fitting.

In the vertical ducts of the system or those running substantially vertical, I employ a somewhat different type of tile which is shown more in detail in Fig. 5. The tile for this vertical duct comprises a body portion 7 and a cup socket portion considered as a whole at 8. This cup socket is formed to have a projecting shoulder 8a, adapted to hold the tubular body portion of the adjoining tile shown at 7a. The upper part of this cup socket or that part shown at 8b is hollowed out to form a bell-shaped receptacle about the tubular body portion of the adjoining tile. It will be readily seen that by using this type of tile in the vertical ducts that the moisture and water from the subsoil will collect in the bell-shaped cup formed by the flaring lip 8b and will seep down through the tile connections and be drained off through the system. On the other hand, in the horizontal ducts or those previously explained, the water will collect in the longitudinal channels 4 and seep down between the upper and lower tile portions and thence be carried off through the drain ducts.

In case the soil to be drained is of heavy loam or clay, or any type of soil through which the moisture does not readily per-

meate, it may be desirable in laying the tile to place gravel, crushed rock or any granular substance available in the longitudinal channels 4 of the horizontal ducts and in the 5 cup socket portion of the vertical ducts. The use of this material will materially aid the water in seeping into the channels and cup socket portions and thence into the drains.

As is commonly known, the facilitating of 10 the egress of the water is not alone the essential factor in draining the subsoil but some provision must be made for supplying air thereto. This type of tile lends itself readily to the circulation of air through the crevices 15 between the upper and lower portions of the tile sections of the horizontal ducts and between the tubular body and the cup socket connections of the vertical ducts.

The drain tile here explained for use in 20 the horizontal ducts of a drainage system are adaptable also to use in surface drains, the lower portion being sunk in a trench and held fixedly from any rotary movement by the shoulders 3^b of the flange portions. Surface 25 drains of this sort could be readily cleaned by merely removing the top section.

In the construction of these tiles I preferably use a vitrified clay which is practically impervious to water and does not readily 30 waterlog. The space between the tile sections made by the tile construction are ample to care for all the water in the subsoil without the necessity of using a porous tile.

In this I do not wish to limit myself to 35 any particular substance in the construction of the tile or to any particular means for collecting the water from the subsoil further than that stipulated in the specification and claims. The advantage in this tile lies solely 40 in the construction by means of which the subsoil moisture may be easily collected and drained off, and at the same time the subsoil supplied with air by a free circulation through the ducts and crevices especially 45 provided for this purpose.

I claim as my invention:

1. In drain tiles, the combination with a pair of abutting tubular members, of an enlarged flange portion secured to the end of 50 one tile member and fitting around the abutting end of the other tile, a cup shaped portion carried by said flange and adapted to collect the moisture from the subsoil and permit the seepage through the tiles into the 55 system.

2. In drain tiles, the combination with a pair of abutting tubular members, of an en-

larged flange portion at one end of the tile member, a shoulder portion within the flange portion fitting around the abutting end of 60 the other tile, a bell shaped mouth on said enlarged flange portion for collecting the subsoil moisture, and adapted to drain the collected moisture into the system.

3. In drain tiles, the combination with upper and lower semi-cylindrical sections, overlapping flanged sockets on the longitudinal edges of said lower section adapted to carry the upper section, a bell mouthed end connection on the upper and lower sections for 70 uniting the ends by a bell and spigot connection.

4. In drain tiles, the combination with upper and lower semi-cylindrical sections, enlarged overlapping flanged portions on the 75 longitudinal edges of the lower sections, a flaring lip on the flanged portions adapted to collect the subsoil moisture, and means for making end unions of the separate tile sections.

5. In drain tiles, the combination with upper and lower semi-cylindrical sections, overlapping flange portions on the longitudinal edges of said lower section for supporting the upper section, bell mouthed flanges on 85 both the upper and lower sections for end-wise connecting the separate tile sections into continuous ducts.

6. In drain tiles, the combination with a tubular body member of a bell mouthed end 90 flange connection adapted to fit the tubular body member of the adjoining tile, a flaring lip on each flange connection for collecting moisture therein, and for draining said moisture into the tiles.

7. In drain tiles, the combination with a tubular body member, of an enlarged cup socket end flange connecting portion comprising an inner shoulder adapted to fit around the tubular body member of the adjoining tile and a flaring lip portion forming a cup-shaped receptacle about the tubular body of the adjoining tile.

8. In drain tiles, the combination with upper and lower semi-cylindrical sections, overlapping flange portions on the longitudinal edges of the lower sections adapted to support the upper section in position on an open joint and permit the ground water collected thereby to flow into the drain, bell mouthed connection on one end of the section adapted to be connected with the adjoining tile sections by a bell and spigot joint.

EMORY E. TROWBRIDGE.
